UNITED STATES PATENT OFFICE.

THOMAS F. DALY, OF NEW YORK, N. Y.

BLACKBOARD.

SPECIFICATION forming part of Letters Patent No. 627,396, dated June 20, 1899.

Application filed December 31, 1898. Serial No. 700,852. (No model.)

To all whom it may concern:

Be it known that I, THOMAS F. DALY, a citizen of the United States, residing at Brooklyn borough, city of New York, in the county of Kings and State of New York, have invented new and useful Improvements in Blackboards, of which the following is a specification.

This invention relates to improvements in blackboards; and it consists in the construction and arrangements of the parts, as will be hereinafter set forth, whereby I provide a blackboard which consists of a fixed writing-surface or a frame which contains a blackboard, a movably-supported case having therein a plurality of slides or blackboards, the parts being so organized that the case may be positioned with respect to the fixed board, so that the slides may be adjusted to cover either end of the fixed board or the inner slides carried by the case, the construction also embodying means whereby the case may be turned upon its support to expose the opposite sides of the slides and either end of the fixed board, the construction also providing means for holding the slides in a fixed position and supporting the ends thereof which are positioned beyond the case.

In the accompanying drawings, which illustrate my invention, Figure 1 is a perspective view of a blackboard embodying my improvements. Fig. 2 is a front elevation; and Fig. 3 is a side view, the case being shown as positioned away from the fixed board.

Referring to the drawings, A designates a blackboard as usually constructed, which is mounted in a frame rigidly attached to a wall or other surface. On a line with the center of the board A are secured two plates b b', having vertical bearings for the ends of arms B B', which arms swing freely in the bearings, the upturned end of the upper arm B having a nut which serves to provide means for causing frictional engagement of the arm with the bearing to take up any lost motion. The outer ends of the arms B B' have therein longitudinal slots, through which pass pivot-pins b², said pins engaging with plates attached to the upper and lower sides of a case C. The case C consists of a top board c and bottom board c', to which are attached frames c²,

which connect the boards to each other, which boards have parting-strips c³. Between the parting-strips carried by the bottom or under board c' are rollers c⁴, which are spaced at 55 suitable intervals and mounted on journals which pass through the lower board.

D refers to a series of slides or framed boards which are placed within the case and rest upon the rollers carried thereby. These 60 slides have writing-surfaces on both faces and are provided with apertures d in the outer ends of the vertical frames. The case may be of a size to receive quite a number of the slides, and when the case is moved away from the 65 fixed board the order of the slides may be changed.

E refers to stop-boards, which are rigidly attached to the vertical ends of the board A, so as to project at right angles therewith, and 70 these stop-boards carry hand-screws e, which are so positioned as to register with the threaded apertures in the end frames of the slides D. To the wall or support for the board A are secured slotted guides F, with which engage sliding shelves or brackets G, which are adapted to be placed on either side of the stop-boards E, said brackets serving as a support for the ends of the slides which are projected from the case.

In general use the board A is about twice the length of the case C, and when said case is swung either to the right or to the left and moved inward against the frame of the board A one end of the case will abut against one 85 of the stop-boards E, and when in such position the slides D may be moved over the exposed surface of the board A and when so positioned can be made fast to the opposite stop-board, the bracket serving to support the 90 slides until made fast. Should it be desired to reverse the slides, the arms or supports for the case can be moved outward, so as to be at substantially right angles with the board A, and when in such position the case can be 95 turned upon its supporting-pivots.

It will be noted by the construction shown that a board of this construction may be used either for educational uses, as in school-rooms, or for stock-quotations, and the arrangement and construction are such that a large amount of writing-surface is provided

in a small space and that the boards or slides may be covered to keep matter out of sight until desired.

Having thus described my invention, what 5 I claim as new, and desire to secure by Letters Patent, is—

1. In combination with a fixed writing-surface or blackboard, of a case having a plurality of slides, arms which are pivotally attached to fixed supports and to the case together with brackets with which the ends of the slides when projected beyond the case may engage substantially as shown and for the purpose set forth.

15 2. In combination with a fixed writing-surface or blackboard, of a case containing slides, means for supporting the case so that it can be swung toward either end of the fixed blackboard and vertical stop-boards located adjacent to the ends of the fixed board so as to project and be engaged by the case, substantially as shown.

25 3. In combination with a fixed writing-surface and boards which project at right angles from the ends thereof, brackets mounted so as to be movable in front of or to one side of the board, of a case containing a plurality

of slides, arms for supporting the case so that it may be turned or caused to abut against either of the projecting boards, and means 30 carried by the projecting boards for engagement with the slides substantially as shown and for the purpose set forth.

4. In a blackboard the combination of a fixed board or writing-surface, arms pivotally 35 attached to supports positioned centrally with respect to the board, a case carried by the outer ends of the arms, a plurality of slides carried by the case, stop-boards positioned at the ends of the fixed board so as to be engaged by the ends of the case, means carried by the stop-boards for engagement with the slides carried by the case and brackets supported so as to be moved to either side of the stop-boards to provide supports for the slides when 40 projected from the case, substantially as shown and for the purpose set forth.

In testimony whereof I have hereunto set my hand in presence of two subscribing witnesses.

THOMAS F. DALY.
